Attty.

UNITED STATES PATENT OFFICE

OWEN KENT, OF DOWNERS GROVE, ILLINOIS, ASSIGNOR TO BRIEDE & ROGOVSKY, OF CHICAGO, ILLINOIS, A COPARTNERSHIP CONSISTING OF HENRY J. BRIEDE AND W. P. ROGOVSKY

MACHINE FOR BENDING TROUSER HOOKS

Application filed June 1, 1928. Serial No. 282,063.

Heretofore it has been common practice to make hooks for trousers, or the like, and then fasten the completed hook to the goods by sewing, but as set forth in my application for Method and apparatus for applying trouser hooks, filed March 26, 1928, Serial No. 264,727, I provide a new system of applying hooks whereby the hook blanks are made and fastened to the goods and then the blank is bent to form the hook. The present invention relates particularly to means for bending or completing such hook members.

The objects of this invention are to provide a simple and effective mechanism for bending trouser hooks and the like; to provide means whereby a blank or partially formed hook is bent to complete the hook after such blank has been secured in position on the goods; and to provide such other advantages and desirable features as will appear more fully hereinafter.

In the accompanying drawings illustrating this invention,

Figure 1 is a side view of my improved bending machine;

Figure 2 is a front view of the same;

Figure 3 is an enlarged sectional detail taken on the line 3—3 of Figure 5 showing the parts in position for the bending action;

Figure 4 is a similar view showing the completion of the bending;

Figure 5 is a detail plan view of the bending devices; and

Figure 6 is a view showing the hook blank in dotted lines as applied to the garment and the completed hook portion in full lines.

In the particular form of the machine as shown in these drawings, the frame 7 is provided with a support or anvil 8 upon which the garment 9 with the hook blank 10 is supported, as shown in Figures 3 and 4. It is understood that the blank or partially formed hook is secured in position in the trouser corner or garment by sewing or otherwise preparatory to bending. A foot or clamping member 11 coacts with the anvil or clamping member 8 for holding the garment and hook blank in position. The foot 11 has a forwardly extending projection or

ing end of the blank is bent to form the hook, as shown in Figure 4. The foot 11 is carried on a rod or shaft 13 which passes through bearings 14 and 15 in the frame 7. This rod is held in normally raised position by means of a spring 16 which is interposed between the bearing 14 and a collar 17 on the shaft. A lever 18 is pivoted at 19 to an arm 20 on the frame 7 and is suitably attached to the rod 13 as by means of a pin 21 for reciprocating the rod. The lever 18 may be actuated in any convenient manner, as by means of a rod 22 and pedal (not shown).

A guide 23 is arranged at the front of the anvil 8 and is secured thereto in any convenient manner, as by means of a screw 24 which passes through a slot 25 in a flange 26 at the lower portion of the guide. An adjusting screw 27 is also provided for accurately adjusting the position of the guide in order to insure the bending of the hook at the proper point. The guide 23 is shaped to conform with the outer portion of a hole 28 in the blank 10 so that when the blank is fitted thereto it will be held accurately in position.

A yoke 29 is pivoted at 30 to the anvil 8 and is adapted to swing in a vertical plane. This yoke has two inwardly projecting rollers 31 which are pivoted to the sides thereof, as shown particularly in Figures 3 and 5, and which are adapted to engage with the outer end of the blank to complete the bending operation. These rollers preferably approach the guide 23 as closely as possible in order to engage with a substantial portion of the hook blank. The yoke 29 has a bent arm or rod 32 which is provided with a handle 33 which is arranged so that the yoke may be easily swung by the operator and the handle will not interfere with the garment or operating parts.

When the hook is to be completed, the operator places the trouser or garment, as indicated at 9, on the anvil with the hook blank 10 fitting over the body 23 and engaging closely therewith. The foot 11 is then brought down and held securely in position on the garments during the forming operation. While the garment is thus clamped securely in position, the handle 33 is swung

to raise the yoke, and the rollers 31 engage the projecting end of the blank 10. As the rollers move upwardly and inwardly they bend the blank over the foot 12, as shown in Figure 4, and press it closely against the foot which is preferably slightly curved or shaped to give the outer portion the desired form. As soon as the hook is completed the yoke is swung downwardly to its original position, the foot raised and the garment removed therefrom. This operation may be rapidly done even by unskilled labor and the completed hooks will be uniformly positioned with respect to the goods and suitably shaped to give the best results.

While the hooks referred to herein are intended particularly for trousers, it is obvious that they may be applied to other garments and my improved machine utilized for forming the same. Changes may be made in the design or arrangement of the parts in order to adapt the machine for different sizes or forms of hooks for different conditions; therefore I do not wish to be limited to the exact arrangement herein shown and described, except as specified in the following claims, in which I claim:

1. In a machine for bending garment hooks having holes therein, the combination of a frame having an anvil for supporting a hook blank, a presser foot coacting with the anvil for holding the blank, means for actuating said presser foot, a guide adjacent to the anvil for engagement with the holes in the hook blank, and a movable forming member adapted to engage with the blank for bending the same over a portion of the presser foot.

2. A machine for bending trouser hooks, comprising a frame having a clamping member adapted to support a portion of the trousers with a hook blank secured thereto, a presser foot adapted to engage with the garment and blank for clamping the same on the clamping member, means for actuating said presser foot, an adjustable guide adjacent to the clamping member for guiding the blanks, a yoke pivoted to the clamping member, rollers on said yoke for engagement with the blank, and means for swinging the yoke, the arrangement being such that the rollers will bend a portion of the blank over and against a portion of the presser foot which serves as a form for the completed hook.

3. A machine for bending trouser hooks, comprising a frame, a support in said frame, a vertically arranged shaft mounted in said frame above the support, resilient means tending to hold the shaft in raised position, manually operable means for depressing the shaft, a combined clamping and forming member carried by the shaft and adapted to coact with the support for holding the trouser corner with a hook blank secured therein, a guide mounted on the support and

adapted to fit in a hole in the hook blank, a forming member pivoted to the support, bending and forming rolls carried by said forming member, and means for swinging the forming member, the arrangement being such that when the forming member is swung upwardly the rollers will engage with the projecting portion of the blank and bend and press the same against said clamping and forming member.

4. In a device as per claim 3, a guide formed to fit a hole in the hook blank and means for adjustably supporting said guide.

OWEN KENT.
